[57] ABSTRACT

A creeper attachment for a shoe which includes a partial sole that underlies a shoe sole. A band member having a row of spike assemblies is attached to the partial sole. Ends of an elastic strap are attached to the band member. The elastic strap extends around a heel portion of the shoe to hold the attachment on the shoe.

CREEPER ATTACHMENT

This invention relates to a creeper attachment for a shoe.

In inclement and icy weather, ordinary shoes or rubbers may not give sufficient traction to the feet. In addition, on rough ground, spikes are often of help, but such spikes need to be removed before one walks on an inside floor.

An object of this invention is to provide a readily removable creeper attachment for a shoe which includes spikes which can assist in walking on rough ground or on icy surfaces.

A further object of this invention is to provide such an attachment which grips the shoe at a position just forward of the instep portion of the shoe and is firmly held in place thereon.

A further object of this invention is to provide such an attachment for the shoe which can readily be mounted on and removed from the shoe.

Briefly, this invention provides a creeper attachment for a shoe which includes a band which can surround the portion of the shoe just forward of the instep portion. A partial sole is attached to the band underlying the sole of the shoe. Spike elements are attached to the partial sole, and a row of the spike elements is attached to the band as well as to the partial sole to hold the band and the partial sole in assembled relation. An elastic strap is attached to the band and extends around a heel of the shoe to hold the attachment in position. Laces are provided at ends of the band for adjusting the length of the band so that the band can be fitted to the shoe.

The above and other objects and features of the invention will be apparent to those skilled in the art to which this invention pertains from the following detailed description and the drawings, in which:

FIG. 1 is a perspective view of a shoe with a creeper attachment mounted thereon, the creeper attachment being constructed in accordance with an embodiment of this invention;

FIG. 2 is a view in side elevation of the creeper attachment, laces thereof being removed;

FIG. 3 is a view in end elevation of the creeper attachment, looking in the direction of the arrows 3-3 in FIG. 2, the laces being shown in dashed lines;

FIG. 4 is a view in section taken generally on the line 4-4 in FIG. 3 with laces removed; and

FIG. 5 is a bottom plan view of the creeper attachment.

In the following detailed description and the drawings, like reference characters indicate like parts.

In FIG. 1 is shown a creeper attachment 10 constructed in accordance with an embodiment of this invention, which is shown mounted on a shoe 12. The shoe 12 can be a conventional shoe having a sole 13 and a heel portion 14.

The creeper attachment 10 includes a band member 16 which can extend around the portion of the shoe which is just in front of the instep. Eyes 17 are formed in the band portion 16 adjacent free edges thereof as shown in FIGS. 2 and 4. A lace 18 (FIGS. 1 and 3) is threaded through the eyes 17, and ends of the lace 18 can be tied together to hold the ends in position to adjust the effective length of the band member 16. The band member 16 can be formed of leather or leather-like plastic material. A partial sole 19 of rubber or

other rubber-like material is attached to the band member 16 centrally thereof. The band member 16 is attached to the partial sole 19 by means of a row of spike assemblies 22. Each of the spike assemblies 22, as shown in FIG. 4, can be of usual form and includes a base portion 24 and a spike portion 26. The base portion 24 includes an internally threaded shank 28, an outwardly extending annular flange 29 which overlies the band member 16, and prongs 31 on the flange 29 which extend into the band member 16 to lock the base portion 24 in place. The spike portion 26 includes an externally threaded shank 33 which is threaded in the shank 28 of the base portion 24, an annular flange 34 which engage the underside of the partial sole 19, and a spike head 36 which extends downwardly therefrom. Additional similar spike assemblies 22A are mounted in the partial sole 19 on opposite sides of the band member 16 as shown in FIG. 5.

An elastic strap 41 is attached to the band member 20 16. As shown in FIG. 5, end portions 42 of the strap 31 are folded around side sections of the band member 16, and the end portions 42 are attached to the band member 16 by stitching 43 (FIGS. 2 and 4). The elastic strap 41 can extend around the heel portion 14 of the shoe 25 12 as shown in FIG. 1 to hold the creeper attachment 10 in position on the shoe 12 with the partial sole underlying the ball portion of the shoe, i.e., the portion of the shoe in front of the instep.

The creeper attachment illustrated in the drawings 30 and described above is subject to structural modification without departing from the spirit and scope of the appended claims.

Having described my invention, what I claim as new 35 and desire to secure by letters patent is:

1. A creeper attachment for a shoe which comprises a partial sole for underlying a portion of a sole of the shoe, a one-piece band member having a central portion overlying the partial sole, a row of spike assemblies attaching the central portion of the band member to the partial sole, each of the spike assemblies including a spike head extending downwardly from the partial sole, means for linking ends of the band member, an elastic strap, and means for attaching end portions of the elastic strap to the band member on opposite sides of the central portion, the band member being adapted to engage the shoe in front of an instep portion, the elastic strap being adapted to engage a heel portion of the shoe to hold the attachment on the shoe.

2. In combination with a shoe, a creeper attachment 50 which comprises a partial sole underlying a portion of a sole of the shoe, a one-piece band member having a central portion overlying the partial sole, a row of spike assemblies attaching the central portion of the band member to the partial sole, each of the spike assemblies including a spike head extending downwardly from the partial sole, means for linking ends of the band member, an elastic strap, and means for attaching end portions of the elastic strap to the band member on opposite sides of the central portion, the band member engaging the shoe in front of an instep portion, the elastic strap engaging a heel portion of the shoe to hold the attachment on the shoe.

3. A creeper attachment for a shoe which comprises a partial sole for underlying a portion of a sole of the shoe, a one-piece band member having a central portion overlying the partial sole, means attaching the central portion of the band member to the partial sole, a

plurality of spike assemblies mounted on the partial sole, each of the spike assemblies including a spike head extending downwardly from the partial sole, means for linking ends of the band member, and elastic strap, and means for attaching end portions of the elastic strap to the band member on opposite sides of the

central portion, the band member being adapted to engage the shoe in front of an instep portion, the elastic strap being adapted to engage a heel portion of the shoe to hold the attachment on the shoe.
